COMBINATION CHALK BOARD MOLDING
STRIP AND MAP DISPLAY RAIL HOOK
SUPPORTING MEMBERWayne T. Jervis, Flossmoor, Ill., assignor to
Weber Costello Company, Chicago Heights, Ill.,
a corporation of Illinois

Application June 6, 1950, Serial No. 166,328

2 Claims. (Cl. 35—67)

1

This invention relates to a combination chalkboard molding strip and map display rail hook supporting member and is an improvement upon the map display rail and hook supporting member which is disclosed in Elmer W. Christy Patent No. 1,930,965 granted October 17, 1933, on "Display Rail and Hook."

An object of the present invention is to provide a new and improved combination chalkboard molding strip and map display rail hook supporting member which may be used advantageously in conjunction with chalkboards in school rooms and like places, for retaining the upper edge portion of a chalkboard in position of use upon and against a vertical wall surface while, at the same time, providing a support for a map display rail hook supporting member such as that which is disclosed in the aforesaid Patent No. 1,930,965.

Another object of the present invention is to provide a new and improved and relatively simple and inexpensive combination chalkboard molding strip and map display rail hook supporting member having a unique and pleasing design and appearance which are such that it may be used as a chalkboard molding strip, per se, as and when desired, and without modification or reconstruction, while, at the same time, being available for use as a map display rail hook supporting member if it should be desired to use the new chalkboard molding strip for that additional purpose and function.

Other objects will appear hereinafter.

Fig. 1 is a front elevational view illustrating the new combination chalkboard molding strip and map display rail hook supporting member in position of use in conjunction with a chalkboard and upon the vertical wall of a schoolroom or like place;

Fig. 2 is an enlarged fragmentary elevational view of the construction shown in Fig. 1;

Fig. 3 is a fragmentary vertical sectional view on line 3—3 in Fig. 2;

Fig. 4 is a top plan view on line 4—4 in Fig. 2, partly in section; and

Fig. 5 is a fragmentary enlarged sectional view similar to Fig. 3 but showing the map display rail hook supporting member in the position which it assumes when being introduced into and removed from the new combination chalkboard molding strip and map display rail hook supporting member.

A preferred embodiment of the new combination chalkboard molding strip and map display rail hook supporting member is illustrated in the drawing, wherein it is generally indicated at

2

10, and is shown as being used in conjunction with chalkboard 11 which is mounted upon the surface 12 of a vertically extending wall 13 in a school-room or like place.

5 The new combination chalkboard molding strip and map display rail hook supporting member is formed as a one-piece unitary metal strip, suitably cast or extruded through a forming die from suitable metal such, for example, as an aluminum alloy, and comprises a body 14 having an inclined upper edge 15 and including an upwardly extending attaching flange portion 16 at the rear thereof. This attaching flange portion 16 is attached to the vertically extending wall 13 by means of suitable fastening elements, such as the screw 17.

The new combination chalkboard molding strip and map display rail hook supporting member 10 has a notched or indented portion 18 on its rear surface (Fig. 3) and in use this notched or indented portion 18 overlies and rests upon the top edge of the chalkboard 11.

The new combination chalkboard molding strip and map display rail hook supporting member 10 also includes a vertically extending and depending flange 19 which, in use, extends downwardly across the face of the upper end portion of the chalkboard 11 so as to retain the chalkboard 11 firmly against the vertically extending wall 13 of a schoolroom or like place, as shown in Fig. 3.

The new combination chalkboard molding strip and map display rail hook supporting member also has a substantially channel-shaped guideway 20 formed therein and extending 35 lengthwise therethrough. This guideway 20 is formed, in part, by a horizontally extending ledge or flange 21, which is arranged at the bottom thereof, and this horizontally extending ledge or flange 21 projects inwardly from a vertically extending wall 22 which projects downwardly from the body 14 at the front thereof, and forms the front wall of the substantially channel-shaped guideway 20. As shown in Fig. 3, the top of the guideway is formed by the body 40 14 of the new combination chalkboard molding strip and map display rail hook supporting member.

The channel-shaped guideway 20 has an inlet opening or mouth 23, at the inner end thereof, for a purpose which will be described presently.

A map display rail hook supporting member is generally indicated at 24 in the drawing and is of substantially the same construction as the map display rail hook supporting member disclosed in the aforesaid Patent No. 1,930,965, and com-

prises an elongated and substantially flat metallic body 25 having a map display rail supporting hook 26 formed integral therewith at one side thereof. As shown in the drawing, this hook 26 projects forwardly of the map display rail hook supporting member 24. The body 25 of the hook 24 has a rightangularly extending upper end portion 30.

A substantially flat leaf spring member 27 is mounted upon the face of the body 25 of the hook 24 and is suitably attached thereto between its ends as by means of a rivet 28. The upper end portion 29 of the flat leaf spring member 27 is normally bowed slightly outwardly from the body 25 of the hook 24, and this end portion 29 of the flat leaf spring member 27 terminates slightly short of the angled end portion 30 of the body 25 of the hook 24.

In the use of the new combination chalkboard molding strip and map display rail hook supporting member 10 the same may be mounted in position of use, as shown, with the horizontally extending edge 18 thereof disposed above and resting upon the top edge of a chalkboard 11 and with the upwardly extending attaching flange 16 of the member 10 attached to a vertical wall surface 13, as by means of the screw 17, so as to retain the chalkboard 11 firmly thereagainst.

When so disposed, the new combination chalkboard molding strip and map display rail hook supporting member 10 not only functions as a chalkboard molding strip, to retain the upper edge portion of the chalkboard 11 firmly against the vertical wall surface 13, and in position of use thereon, but is also useful for supporting the map display rail hooks 24.

The map display rail hooks 24 are adapted to support a display roll map 31 in position of use upon the chalkboard 11 and to accomplish this result a pair of the map display rail hooks 24 may be mounted in position of use in spaced relationship, as shown in Fig. 1. In order to mount the map display rail hooks 24 in position of use upon the new combination chalkboard molding strip and map display rail hook supporting member 10 the hooks 24 are positioned at an acute angle relative to the member 10 and chalkboard 11, and the upper end portion 29 of the flat leaf spring 27 compressed slightly inwardly against the body 25 of the hook 24. The rightangularly extending upper edge portions 30 of the map display rail hooks 24 are thereupon inserted through the mouth or throat 23 into the channel-shaped guideway 20 whereupon the hooks 24 are manipulated relative to the substantially channel-shaped guideway 20 and the body 14 of the combination chalkboard molding strip and map display rail hook supporting member 10 until the rightangularly extending upper edge portion 30 rests upon the horizontally and inwardly extending ledge or shelf 21 of the member 10, and the body 25 of each hook 24 extends substantially vertically and bears against the face 11 of the chalkboard 11, as shown in Fig. 3. When so disposed the upper end portion 29 of each flat leaf spring member 27 bears against the inner edge of the ledge or shelf 21 and serves to keep the hooks 24 in proper position.

When so disposed, the trunnions 32 of a roll display map 31 may be rested upon the hook portions 26 of the hook 24, as shown in the drawing.

In order to remove each hook 24 from the substantially channel-shaped guideway 20, it is merely necessary manually to press the upper

end portion 29 of the flat spring member 27 slightly inwardly against the flat metal body 25 of the hook 24, then rotate the hook 24 clockwise, as indicated in Fig. 5, so as to retract the rightangularly extending upper end portion 30 thereof out of the channel-shaped guideway 20, through the mouth or throat 23.

The new combination chalkboard molding strip and map display rail hook supporting member provides a novel dual purpose unit in that not only does it function to provide a chalkboard molding strip for retaining the upper edge portion of the chalkboard 11 firmly against the vertically extending wall surface 13, but it also serves as an efficient support for the map display rail hooks 24.

Moreover, the new combination chalkboard molding strip and map display rail hook supporting member may be used as a chalkboard molding strip, per se, independently of the map display rail hooks 24, and when so used provides an efficient chalkboard molding strip which is simple and efficient in construction and has a novel and pleasing ornamental design and appearance.

It will thus be seen from the foregoing description, considered in conjunction with the accompanying drawing, that the present invention provides a new and improved combination chalkboard molding strip and map display rail hook supporting member having the desirable advantages and characteristics, and accomplishing its intended objects, including those hereinbefore pointed out and others which are inherent in the invention.

I claim:

1. A combination chalkboard molding strip and map display rail hook supporting member comprising an elongated unitary body having a horizontally extending portion adapted to be rested upon the upper edge portion of a vertically extending chalkboard and having an attaching flange formed as an integral part thereof and extending substantially vertically upwardly therefrom at the rear thereof for attaching the said body to a vertically extending wall surface at the rear of the said chalkboard, the said body having a substantially vertically extending flange depending therefrom at the front thereof and adapted to extend downwardly over the upper front face portion of the said chalkboard so as to retain the said chalkboard in position of use against the said unitary body having a substantially channel-shaped guideway formed therein and extending lengthwise therethrough, said substantially channel-shaped guideway having a closed top wall and a closed front wall and a bottom wall in the form of a flange extending horizontally rearwardly from the said front wall 60 of said elongated unitary body to a point disposed forwardly of the said depending flange of said unitary body, said unitary body having a vertically extending throat at the bottom and rear of the said substantially channel-shaped guideway and between the inner rear end of the said horizontally extending flange and the adjacent front surface of said depending flange and through which said throat an angled upper end portion of a map display rail hook supporting member may be introduced between the inner rear end of the said rearwardly extending bottom flange and the front surface of said depending flange into the said substantially channel-shaped guideway so as to be rested upon and supported by and upon the said horizontally ex-

tending bottom flange of the said unitary body.

2. A combination chalkboard molding strip and map display rail hook supporting member as defined in claim 1 in which the said unitary body has an inclined upper surface which is inclined upwardly from its lower end to its front end, and in which the said unitary body has a front end portion extending substantially vertically downwardly at the front end of the said inclined upper surface and merging at its lower 10 end into the outer front end portion of the said horizontally extending flange.
